UNITED STATES PATENT OFFICE.

SAMUEL KELLETT, OF SAN FRANCISCO, CALIFORNIA.

DESIGN FOR CENTER-PIECE.

Specification forming part of Design No. 6,328, dated December 24, 1872.

To all whom it may concern:

Be it known that I, SAMUEL KELLETT, of the city and county of San Francisco, State of California, have invented or produced a new Design for Center-Piece; and I do hereby declare that the following is a full, clear, and exact description of the same, reference being had to the accompanying photograph or drawing, and to the letters marked thereon.

My new design may be styled Grecian, and consists of a rosette, *a*, from which extends a series of radial arms, *b b b*, between which are placed strings of button-work *c c c*, the whole being surrounded by a plain molding, *d*. Between the inner molding *d* and a plain outer molding, *e*, is placed a chain-work of daisies, *f*, and daisies and flowers *g*, bound at intervals with straps *h*, whose outer ends overlap the

outer molding *e*. This chain-work is surrounded or edged by shell-work *i j*.

Having thus described my invention, what I claim, and desire to secure by Letters Patent, is—

1. The radial arms *b b* and button-work *c c*, as set forth and described.
2. The chain-work of daisies *f*, flowers *g*, and straps *h*, as set forth and described.
3. The edge-work *i j*, as shown.
4. The design for center-piece, as set forth and described.

In witness whereof I have hereunto set my hand and seal.
